United States Patent Office.

FRANCIS H. WILLIAMS, OF SYRACUSE, NEW YORK.

Letters Patent No. 78,851, dated June 9, 1868.

IMPROVEMENT IN THE CONSTRUCTION OF SAFES.

The Schedule referred to in these Letters Patent and making part of the same.

TO ALL WHOM IT MAY CONCERN:

Be it known that I, FRANCIS H. WILLIAMS, of Syracuse, in the county of Onondaga, and State of New York, have invented certain new and useful Improvements on Safes and Vaults; and I do hereby declare that the following is a full, clear, and exact description thereof, reference being had to the accompanying drawings, making part of this specification, in which—

Figure 1 is a perspective view of a safe having my improvements applied to it.

Figure 2 is a horizontal section through the safe-door and frame, the door being closed and bolted.

Figure 3 is a view of the inside of the safe-door and frame.

Figures 4 are perspective views of the hinges used in conjunction with my improved safe-door.

Similar letters of reference indicate corresponding parts in the several figures.

This invention relates to certain novel improvements on safes or vaults which are designed for the repository of valuable articles. It consists primarily in fitting the door of a safe or vault into the frame or jamb thereof, by means of acute-stepped edges, in such manner that the door shall be required to move bodily and squarely from its seat a certain distance before it is allowed to swing open upon its hinges; and in applying hinges to a door which is hung in the aforesaid manner, so that these hinges will allow it to be moved in a straight line, as well as to swing about an axis, and also afford it a good support, whether open or shut, as will be hereinafter described.

To enable others skilled in the art to understand my invention, I will describe its construction and operation.

In the accompanying drawings, A represents the door of a safe or vault, which is constructed of the form of the frustum of a pyramid, with stepped edges, *h i*, adapted to fit snugly against corresponding stepped edges, *h' i'*, which surround the jamb of the door, as shown in fig. 2.

The abutting surfaces, *i i'*, of the door and its jamb are all made to fit snugly when the door is closed. This is also the fact with regard to the bevelled surfaces, *h* and *h'*, which, with the surfaces *i i'*, form acute angles or steps. These steps may vary in size and number, as may be required, and they may be made more or less acute, as circumstances require.

The surfaces *i i'* of the steps are perpendicular to the plane of the external surface of the front plate D, and are thus made for the purpose of preventing the door A from being swung open and shut in the usual manner. To open or close this door A, it will be necessary to move it squarely outward until the angles of its steps will clear those upon the jamb, when it may be swung back upon its hinges. Similar movements are required to shut the door.

The ordinary safe-door hinges will not answer for my improved door, for the reason that such hinges allow but a single vibrating movement. I therefore employ hinges, each one of which has two leaves, *b b*, pivoted to lugs, *a a*, upon the safe-frame and its door, and jointed by a pin, *c*, as shown in figs. 1, 2, and 4. The pin *c* of each hinge may be made removable, so that when the door A is shut and fastened the hinges can be made to lie closely to the safe, as shown in figs. 4.

These compound hinges will allow the door A to be moved squarely and bodily toward and from its seat or jamb, and they will also allow the door to swing or vibrate when released from its frame or jamb.

Surrounding the opening or entrance into the safe, and upon the outer surface of the front plate or wall of the safe, is a bead, B, which may be made of a half-round form, as shown in figs. 1 and 2. This bead is arranged close to the edge of the door A, when this door is shut, as shown in fig. 2, and not only affords a close joint around the door, but also serves, in conjunction with the rounded external edge of the door, to prevent the successful use of a wedge or crow-bar in an attempt to prise open the door.

As a means for fastening a safe-door which is constructed so as to open and shut, as above described, I employ four bolts, E E, upon the inner end of a rocking-bar, C, which bar passes through the centre of the door A, and is constructed with a shoulder at *p*, for preventing it from being driven inward. These bolts, E, radiate from the axis of their bar, C, and are arranged at regular distances apart, so that when in the position shown

in fig. 2, they will fasten the door at its four sides, and when turned, as indicated in dotted lines in fig. 3, they will allow the door to be opened. I have not shown a locking-device applied to the bolts E, for the reason that any well-known locking-device, which is adapted for a rocking-bar, C, will answer this purpose.

Having described my invention, what I claim as new, and desire to secure by Letters Patent, is—

1. So constructing and hinging the safe-door A, and fitting it into the frame D, that this door shall be allowed to move bodily and squarely up to and from its seat without being rotated within the door-casing, substantially as described.

2. Fitting the door A to its frame D, by means of acute-angular stepped faces h h' i i' , substantially as described.

3. Providing the double-leaf hinges b b with a removable pintle, c, when such hinges are applied upon the door of a safe or-vault, substantially as and for the purposes described.

FRANCIS H. WILLIAMS.
